W. P. SHEETS.

PIPE WRENCH.

APPLICATION FILED SEPT. 14, 1916.

1,209,049.

Patented Dec. 19, 1916.

Fig. 1.

UNITED STATES PATENT OFFICE.

WILLIAM P. SHEETS, OF PRINCETON, MISSOURI.

PIPE-WRENCH.

1,209,049.

Specification of Letters Patent. Patented Dec. 19, 1916.

Application filed September 14, 1916. Serial No. 120,143.

To all whom it may concern:

Be it known that I, WILLIAM P. SHEETS, a citizen of the United States, residing at Princeton, in the county of Mercer and State 5 of Missouri, have invented a new and useful Pipe-Wrench, of which the following is a specification.

The present invention appertains to pipe wrenches of the "chain" type, and aims to 10 provide a wrench of that character embodying a novel and advantageous assemblage of the component elements, to enhance the utility and efficiency of the wrench.

A further object of the invention is the 15 provision in a wrench of the character described, of a removable and replaceable cushion for the chain assembled with the other parts in a novel manner.

Another object of the invention is the provision of novel means to accomplish the adjustment of the chain operating lever.

It is also the object of the invention to provide a pipe wrench having the characteristics above noted, and which at the same 25 time is comparatively simple in construction, easy and inexpensive to manufacture, and practical and convenient in use.

With the foregoing and other objects in view which will appear as the description 30 proceeds, the invention resides in the combination and arrangement of parts and in the details of construction hereinafter described and claimed, it being understood that changes in the precise embodiment of the invention herein disclosed can be made within 35 the scope of what is claimed without departing from the spirit of the invention.

The invention is illustrated in the accompanying drawing, wherein:—

40 Figure 1 is a side elevation of the wrench, portions of the levers being broken away. Fig. 2 is a longitudinal section, portions being shown in elevation and portions of the levers being broken away. Fig. 3 is a cross 45 section on the line 3—3 of Fig. 1. Fig. 4 is a detail view of the chain attaching or anchor member.

The wrench embodies a pair of levers or 50 handles 1 and 2 of suitable length and swingable toward and away from one another. The outer end portion of the lever 1 is secured or clamped between a pair of side plates 4 by means of rivets 3 or other securing elements, and a transverse bolt or retaining element 5 extends through an aperture 6 with which the lever 2 is provided

adjacent to its outer end, and said bolt 5 also extends through transverse slots 7 with which the plates 4 are provided between their ends. The plates 4 project outwardly 60 beyond the outer end of the lever 1, and the lever 2 has a rounded fulcrum bearing 8 resting against the free end portion of a leaf spring 9 located between the two levers. The inner basal end of the spring 9 is se- 65 cured, by means of a rivet 10 or otherwise, to that side of the lever 1 facing the lever 2, and the spring 9 is located between the plates 4 and projects outwardly. The free portion of the spring 9 rests against the tip of an 70 adjusting screw 11 threaded through the outer end portion of the lever 1 and projecting between the plates 4, whereby the free end portion of the spring 9 is held in various adjusted positions by the screw 11, and 75 the spring 9 forms a fulcrum for the lever 2 against which the bearing 8 rests. There is little or no strain upon the spring 9, since the bearing 8 bears against one side of the 80 spring 9 directly opposite to the adjusting screw 11, so that the strain is transmitted from the lever 2 to the screw 11 almost directly.

The outer end of the lever 2 has an extension 12 projecting beyond the bearing 8, 85 and provided at its free end with a curved tooth or hook 13 to engage the links of a "sprocket" chain 14 employed to grip the pipe P. An arcuate attaching or anchor member 15 has one end of the chain 14 pivot- 90 ally engaged with the free end thereof, as at 16, the free end of the member 15 being bifurcated to receive the end link of the chain, and the butt or basal end of the member 15 has a reduced tongue or extension 17 95 fitted between the outer ends of the plates 4 and secured thereto by means of rivets 18 or the like. The member 15 and corresponding edges of the plates 4 are curved to accommodate pipes of various diameters. 100 There is an opening between the outer end of the lever 1 and member 15 through which the free portion of the chain 14 is passed to be engaged by the hook or bill 13.

In order to prevent the chain 14 from 105 scratching or marring smooth, polished or plated pipes, an elongated gripping cushion 19 is employed, the same being formed from webbing or other suitable material to grip the pipe and provide a cushion for the chain 110 14. The cushion 19 provides a lining for the chain, extending along the inner portion of

the chain between the pipe and chain. One end of the cushion 19 fits against the inner curved surface of the member 15 and is clamped thereagainst by means of a securing bolt 20 extending through the member 15 from its inner to its outer surface. The bolt 20 has a head 21 at its inner end compressed within the cushion 19, as seen in Fig. 2, and a nut 22 is threaded upon the outer end of the bolt 20 to tighten it for clamping the cushion against the member 15.

The screw 11 is ordinarily retracted, whereby the leaf spring 9 moves toward the lever 1 by its tension, thereby permitting the bolt 5 and lever 2 to move toward the lever 1. In applying the wrench to the pipe P, the cushion 19 is passed around the pipe, and the chain 14 passed around the cushion, the cushion and chain being inserted through the opening between the plates 4, and the lever 2 being manipulated to engage the hook 13 with the proper link of the chain. Then, when the two levers are swung toward one another, the lever 2 in rocking upon the spring 9 as a fulcrum, will swing the hook 13 away from the pipe, thereby pulling the chain tightly around the pipe to grip it, and cause the pipe to turn with the wrench. The screw 11 can be screwed to force the spring 9 and lever 2 away from the lever 1, whereby a tighter grip can be obtained under conditions when a sufficiently tight grip cannot be obtained otherwise. The cushion 19 protects the pipe, and affords a perfect grip, even with a smooth or plated pipe. When the lever 2 is released, the hold on the pipe is relieved, whereby the wrench can be swung to a new position to obtain a new hold on the pipe, and this permits the pipe to be turned even when the wrench cannot be oscillated through a large arc, as when the pipe is in a more or less inaccessible position. The wrench has a comparatively wide range of adjustment for use upon pipes of various diameters. The wrench is strong, being capable of resisting severe strains, and it will be noted that the bolt or retaining element 5 is not subjected to shearing strains, since the lever 2 bears against the spring 9 to provide the fulcrum.

Having thus described the invention, what is claimed as new is:

1. A pipe wrench embodying a pair of levers, an adjustable fulcrum for one lever carried by the other, and a chain connected to the second mentioned lever and engageable with the first mentioned lever.

2. A pipe wrench embodying a pair of levers, a leaf spring secured to one lever, an adjusting screw carried by said lever for adjusting said spring, said spring forming a fulcrum for the other lever, and a chain

connected to the first mentioned lever and engageable with the second mentioned lever. 65

3. A pipe wrench embodying a pair of levers, a pair of side plates carried by one lever, the other lever being disposed between said side plates and having a sliding connection therewith, an adjustable fulcrum member for the second mentioned lever carried by the first mentioned lever, and a chain connected to said plates and extending therebetween for the engagement of the second mentioned lever. 75

4. A pipe wrench embodying a pair of levers, a pair of side plates carried by one lever and having slots, the other lever projecting between said plates and having a member working in said slots, a leaf spring secured to the first mentioned lever and projecting between said plates, an adjusting screw carried by the first mentioned lever for moving the spring away from said lever, the second mentioned lever having a rounded bearing seating against the leaf spring to fulcrum the second mentioned lever, and a chain connected to said plates and extending therebetween for the engagement of the second mentioned lever. 85

5. A pipe wrench embodying a pair of levers, a pair of plates carried by one lever and projecting beyond the outer end thereof, an anchor member carried by the outer ends of said plates, the other lever being fulcrumed between said plates, an elongated gripping cushion attached to said member and extending between said plates to surround a pipe, and a chain connected to said member to extend around the cushion between said plates to engage the second mentioned lever. 95

6. A pipe wrench embodying a pair of levers, a pair of plates between which one lever is secured, said plates projecting outwardly from said lever, the other lever being fulcrumed between said plates, an anchor member secured to the outer ends of said plates and curved to accommodate a pipe, an elongated gripping cushion having one end portion fitting the curved surface of said member, a securing element engaging through said member and clamping said cushion thereagainst, and a chain anchored to the end of said member, said cushion and chain being adapted to extend between said plates around a pipe, and the chain being engageable with the second mentioned lever. 105

In testimony that I claim the foregoing as my own, I have hereto affixed my signature in the presence of two witnesses. 120
